UNITED STATES PATENT OFFICE

ERNEST H. PEABODY, OF NEW YORK, N. Y.

APPARATUS FOR PREPARING PULVERIZED FUEL FOR COMBUSTION

Application filed May 24, 1927. Serial No. 193,869.

My invention relates to apparatus for distributing pulverized fuel to burners, the object being to secure a substantially uniform or balanced distribution of the fuel in the carrier air on its way from the pulverizer to the burners, so that each burner will receive substantially the same amount of fuel.

The preparation of coal for "pulverized coal combustion", whether by the circulating system, the indirect system or the unit system, involves various operations including the grinding of the fuel so that a relatively large percentage of it will pass through a 200 mesh screen. In the circulating and indirect systems the pulverized fuel is transported to storage bins from which it is conveyed through large mains around the plant, or by compressed air or mechanical means to the point of consumption. In the unit system the pulverizer is placed near the furnace and the pulverized fuel delivered directly to the furnace or into a small bin, to provide a reserve supply, from which it is distributed by an air blast, known as the carrier air, to the burners. Whatever the system employed, the difficulty has been to secure a substantially uniform distribution of the pulverized fuel throughout the mass as it is delivered to the burners. Moreover, it is of the utmost importance to insure an equal supply of fuel to each burner where a number of burners are installed in a furnace. If the pulverizer prepares fuel for more than one burner it is necessary to divide the single column of air leaving the pulverizer and carrying the total supply of fuel, into a plurality of streams supplying the individual burners. This would be a simple matter if the column of carrier air supporting the pulverized coal, as regards the fuel mixture, was of a homogeneous or balanced character and remained so during its travel to the burners. A condition of uniform mixture, however, does not obtain in actual practice, and, furthermore, any bend

or alteration of direction of the pipe leading to the burners has a tendency to cause the particles of pulverized fuel to group themselves unequally in the stream of air.

In carrying out my invention I receive 50 the stream of carrier air and pulverized fuel, in no matter what degree of unevenness of mixture, and so treat the same as it passes through a distributor as to produce a homogeneous or balanced mixture of the fuel and 55 air, and so that whatever the number of branch pipes leading from the distributor, each will carry substantially the same proportion of fuel.

In the accompanying drawings I have 60 shown apparatus adapted to carry out the present invention and in which Fig. 1 is a vertical section on the plane of the line 1—1, Fig. 2; Fig. 2 is a top view of the distributor; Fig. 3 is a transverse section on the 65 plane of the line 3—3, Fig. 1; Fig. 4 is a transverse section on the plane of the line 4—4, Fig. 1; Fig. 5 is a top view and Fig. 6 is a side view of a modified form of distributor; Fig. 7 is a diagrammatic illustration showing the unequal or unbalanced distribution of pulverized fuel in a column of carrier air, and Fig. 8 is a diagrammatic illustration showing the uniform or balanced distribution of the fuel in the air, or the result which is sought to be accomplished by 70 the present invention.

Various forms of apparatus may be employed for my intended purpose, that illustrated in Figs. 1 to 4 having been found efficient. In these figures, the numeral 1 designates a pipe, preferably vertical, leading from any well known form of pulverizer, not shown. Secured to pipe 1, and preferably 80 in axial alignment therewith, is a cylindrical member 2 in the chamber 3 of which the redistribution or balancing of the fuel in the carrier air is effected. The parts 1 and 2 may be secured together by any suitable 85 means, as by bolts through openings in the 90

flange 2' passing through similar openings in the flange at the upper end of the pipe 1. Supported upon the member 2 is a member 4 into the chamber 5 of which the pulverized fuel after its treatment in the chamber 3, is discharged and from which it is led to the burners through branch distributing pipes 6 secured in openings in the wall of the member 4.

10 Interposed between the flanges of the members 1 and 2, as shown in Fig. 1, is a grid-like member 7 having arms 8 extending from a central hub 9. This hub forms a bearing for the lower end of a shaft 10. In the opening 15 in the bearing 9 is placed a felt ring 11, or other suitable packing to prevent particles of fuel working into the bearing. One of the arms 8 of the grid 7 is formed with a passage 12 leading to a chamber 13 below the 20 end of the shaft. A pipe 14 connects with the outer end of passage 12 to which is attached a grease box from which a suitable lubricant may be fed to the chamber 13. The upper end of shaft 10 extends through a 25 suitable stuffing box 10' and is supported upon ball bearings, not shown located near its top outside of member 4. The shaft is rotated by any suitable means, also not shown.

That part of shaft 10 within the chambers 30 3 and 5 is preferably square in cross section, as shown in Fig. 3, and has attached to it by suitable means, a plurality of blades, four being shown, designated by the numerals 15, 16, 17 and 18. In an apparatus built by me, 35 these blades are approximately $4\frac{1}{4}$ " wide and 24" long. It is obvious, however, that they may vary in number and in dimensions, according to the particular installation made. The blades extend from immediately above 40 the opening from pipe 1 into chamber 3, to the upper or discharge end of said chamber. They divide the chamber 3 into a plurality of compartments, four in the present instance, which, for convenience of description, may 45 be designated by the letters A, B, C and D.

At its upper end, within the chamber 5, the shaft 10 carries a plate 19, the purpose of which is to divert any particles of pulverized fuel which may rise to the top of chamber 5 and throw them back into the streams passing through the distributor pipes 6, thus preventing small particles of fuel getting into the stuffing box 10'.

In operation, the column of carrier air and 55 fuel, as the fuel is delivered from the pulverizer through pipe 1, is, in practice, unbalanced as to the density of mixture. By that is meant, that the fuel is not evenly distributed through the air and has the appearance, as well as it may be illustrated, as 60 shown in Fig. 7. If permitted to flow from chamber 5 in that condition there would obviously be an unequal distribution of the fuel to the several burners. It is therefore the 65 function of the blades as they are rotated in

chamber 3 over the outlet of pipe 1 to divert the stream line of the fuel and air in such manner that successive transverse sections, varying in fuel density will be brought together with more or less turbulence within the chambers defined by the blades and there caused to commingle so that in the resultant mass the fuel will be substantially uniformly distributed throughout the air, as illustrated in Fig. 8. For the purpose of describing 70 the action of the distributor it may be assumed that the carrier air and fuel flow through pipe 1 at the rate of approximately 50' per second. With the shaft rotating approximately 1500 R. P. M., or a single rotation of the blades in one twenty-fifth of a second, and chamber 3 approximately 24" 75 in length, about two lineal feet of the stream will flow through chamber 3 for each rotation of the blades. That is, during a single 80 rotation of the blades, each of the compartments A, B, C and D will receive a portion of each horizontal section of the flowing stream of air and fuel contained within each unit of 2'. The mass within each compartment is an average of the fuel distributed 85 throughout the mass of a given unit. The above rate of flow of the fuel stream, the number of revolutions of the blades and their dimensions are given merely by way of example. These factors may be varied within wide limits according to conditions of the 90 fuel and of the particular installation.

The operation may be further explained by assuming that the quadrants E, F, G and H, in Fig. 7, represent portions of four different transverse sections of the flowing stream, some parts of all of which are received in the compartment A as the blades are rotated through a complete cycle of 360°. As compartment A sweeps over the outlet of pipe 1, it will receive in its initial portions from quadrant E, a certain amount of fuel in a given volume of air; a relatively smaller amount of fuel in its second position, or that corresponding to quadrant F, and an intermediate amount when in its third position, or that corresponding to quadrant G. Similarly, the other compartments formed by the blades, as they sweep over the outlet of pipe 1, will receive successive sections of the stream which will be an average of the total flowing through chamber 3 in a unit of time. These alternate puffs or layers of fuel and air flow through chamber 3, 100 and the relatively small quantities of carrier air varying from rich to lean, as to fuel content, are discharged into chamber 5 in masses in which the fuel is distributed substantially uniformly, thus giving a resultant mass substantially homogeneous as to density.

It will be noted that the blades in their rotation act to displace successive transverse sections of the stream laterally, and to subject the moving stream to a succession of lat- 105 110 115 120 125 130

erally directed impacts, thus bringing about more or less turbulence and a thorough intermingling of the segregated masses distributed through the individual compartments A, B, C and D. Masses of different densities as to fuel content are brought into intimate relation and there is an interflow of the particles of coal from the denser portions to those less dense, by reason of the lateral displacement and sub-division of the stream as it enters chamber 3. In passing out from chamber 5 through a plurality of openings connected with the distributing pipes, each of the pipes will carry away an equal amount of fuel. Thus the mixture of carrier air and fuel as it comes through the pulverizer to pipe 1, although unbalanced to a very considerable degree as to density of mixture, will be delivered into chamber 5 in a condition in which the fuel is distributed or spread evenly throughout the air in said chamber.

In Figs. 5 and 6 I have shown a means for dividing the column of fuel and air by means of a screw 20, which may also be used. As the screw is rotated at a relatively high speed it will slice off a portion of each succeeding horizontal section of the stream of air and fuel and in so doing will so subdivide the stream that as the mass is discharged at the upper end of the screw into the distributing chamber 5, the several portions going to make up the resultant mass will have the fuel in a given unit of the mass uniformly and evenly distributed throughout the air. Whatever means may be employed for dividing up the flowing stream of fuel and air, it must, in order to accomplish the purpose of the present invention, be so proportioned relatively to the velocity of the fuel and air as to divide a given unit of the stream in such a way as to obtain, in the segregated masses, an average of the fuel in the several parts of the stream and to permit the several masses to so commingle as to secure an even or balanced distribution of the fuel in the air as it is discharged into the distributing chamber 5.

What I claim is:

1. In combination with a main conduit for conveying a stream of pulverized fuel and air, a rotatable member in said conduit, a casing forming a chamber into which the fuel laden air is delivered after passing said member, and a plurality of independent distributing pipes leading from said casing.
2. In combination with a main conduit for conveying pulverized fuel and air, a rotatable member in said conduit having blades extending longitudinally of the conduit, a casing forming a chamber into which the fuel laden air is delivered after passing said member, and a plurality of independent distributing pipes leading from said casing.
3. In combination with a main conduit for conveying a stream of pulverized fuel and

air, a casing forming a chamber into which the fuel laden air is delivered, a plurality of delivery pipes leading from said casing, a rotatable shaft extending through said chamber and into said conduit, and a plurality of blades secured to said shaft in said conduit.

Signed at New York city, in the county of New York and State of New York, this 13th day of May, A. D. 1927.
